[57] CLAIM

The ornamental design for a light fixture, as shown and
described.

DESCRIPTION

FIG. 1 is a fragmentary front elevational view of a
fluorescent light fixture showing my new design, the
rear being a mirror image;

FIG. 2 is a fragmentary bottom plan view thereof;

FIG. 3 is a fragmentary top plan view thereof;

FIG. 4 is a left end elevational view thereof;

FIG. 5 is a right elevational view thereof;

FIG. 6 is a fragmentary perspective view thereof, on an
enlarged scale.

The figures are broken away in FIGS. 1, 2, 3 and 6 for
convenience of illustration.

FIG. 1

FIG. 2

FIG. 3

FIG. 4

FIG. 5

FIG. 6
